UNITED STATES PATENT OFFICE

HARRY PULLEN, OF PRESTON, MARYLAND, ASSIGNOR TO INTERNATIONAL PATENTS CORPORATION, OF REHOBOTH BEACH, DELAWARE, A CORPORATION OF DELAWARE

DESIGN FOR A MUSICAL INSTRUMENT OR SIMILAR ARTICLE

Application filed February 4, 1931. Serial No. 38,546. Term of patent 14 years.

To all whom it may concern:

Be it known that I, HARRY PULLEN, a subject of the King of England, and a resident of Preston, in the county of Caroline and State of Maryland, have invented a new, original, and ornamental Design for Musical Instruments or Similar Articles, of which the following is a specification, reference being had to the accompanying drawing, forming part thereof, in which—

Fig. 1 is a top plan view of the article, showing my new design;

Fig. 2 is a side elevation thereof;

Fig. 3 is a bottom plan view thereof;

Fig. 4 is a rear view thereof; and

Fig. 5 is a front view thereof.

I claim:

The ornamental design for a musical instrument, or similar article, as shown.

HARRY PULLEN.
